(57) **CLAIM**

We claim the ornamental design for a glue gun, as shown and described.

DESCRIPTION

FIG. 1 is a side view of a glue gun showing our new design;

FIG. 2 is a top view thereof;

FIG. 3 is a front view thereof;

FIG. 4 is a rear view thereof; and,

FIG. 5 is a bottom view thereof.

The broken line showing the stand is included for the purpose of illustrating unclaimed structure and forms no part of the claimed design.
